PANEL.

No. 17,116.

Patented Feb. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,116, dated February 15, 1887.

Application filed December 30, 1886. Serial No. 223,059. Term of patent 7 years.

To all whom it may concern:

Be it known that I, FREDERICK MANKEY, of Williamsport, Lycoming county, Pennsylvania, have invented and produced a new and original Design for Panels, of which the following is a specification.

Figure 1 of the accompanying photographs represents my design, and Fig. 2 a modification thereof.

10 Similar letters of reference indicate like parts.

My design consists in the rectangular elevation A, having an upper flatsurface and inclined edges. B C D E are quadrangular elevations, 15 also having inclined edges and flat upper surfaces. Between the extremities of elevations B C and D E are rectangular elevations F G. On each side of elevation F are triangular elevations H I, and on each side of elevation G 20 are like triangular elevations, J K. Outside of the elevations F H I and G J K are triangular elevations L M and N O, similar to elevations B C and D E. Finally, between the elevations L M is a triangular elevation, P, 25 and between the elevations N O is a triangular elevation, Q. R S T U are diagonal channels, and V W X Y similar diagonal channels oppositely inclined.

At each end of the design may appear two quadrangular elevations, a b, c d, with channels e f, g h, as shown in Fig. 1. All of said elevations have inclined edges and flat upper surfaces.

I claim—

1. The design for a panel, substantially as herein shown and described, which consists in the rectangular elevations A F G, quadrangular elevations B C D E L M N O, triangular elevations H I J K P Q, and channels R S T U V W X Y, said elevations having 35 inclined edges and flat upper surfaces.

2. The design for a panel, substantially as herein shown and described, which consists in the rectangular elevations A F G, a b, c d, quadrangular elevations B C D E L M N O, 45 triangular elevations H I J K P Q, and channels R S T U V W X Y e f g h, the said elevations having inclined edges and flat upper surfaces.

FREDERICK MANKEY.

Witnesses:

C. F. MANKEY,
LEONHARD KNAUSS.
